UNITED STATES PATENT OFFICE.

JACOB J. LISCH, OF BELLEVUE, KENTUCKY, ASSIGNEE OF ONE-HALF TO FRANK J. GEVERTS, OF BELLEVUE, KENTUCKY.

INSTANTANEOUS WATER-HEATER.

1,069,273.

Specification of Letters Patent. Patented Aug. 5, 1913.

Application filed November 15, 1909. Serial No. 528,003.

To all whom it may concern:

Be it known that I, JACOB J. LISCH, a citizen of the United States of America, and resident of Bellevue, county of Campbell, 5 State of Kentucky, have invented certain new and useful Improvements in Instantaneous Water-Heaters, of which the following is a specification.

This invention relates to water heaters, 10 and particularly to instantaneous water heaters, and means for controlling the delivery of water and gas to the heaters.

An object of this invention is to produce a water heater in which new and improved 15 means are employed for heating the water passing through the heater coils.

A further object is to produce a heater provided with a number of separate coils, each of which is provided with a separate 20 burner, so that the heater is more effective and economical than ordinary heaters.

A further object is to produce a heater in which improved means are employed for controlling the delivery of water and gas to 25 the heater.

A further object is to produce means for controlling the supply of gas to the burners of the heater, which will not deliver gas except when water is delivered to the coils of 30 the heater.

A further object is to produce water and gas delivery valves, which are so constructed that no stuffing boxes are necessary.

These and other objects I attain in an apparatus embodying the features herein described and illustrated.

In the drawings for this application and forming a part thereof, Figure 1 is a perspective view of a heater embodying my invention, a portion of the inclosed casing being broken away for convenience of illustration. Fig. 2 is a sectional elevation of a water supply valve and a gas-supply valve, in connection with a manually operated controlling means for the valves. Fig. 3 is a perspective view of a burner, which forms a detail of my invention. Fig. 4 is a perspective view of a coil-support piece, which may be formed integrally with the burner. Fig. 5 is a perspective view of a pilot burner, which is employed with the apparatus illustrated. Fig. 6 is a sectional view along the line 6—6 of Fig. 2, and illustrates the construction of the water supply valve. Fig. 7 55 is a sectional view along the line 7—7 of

Fig. 2, and illustrates the construction of the gas supply valve.

The apparatus illustrated as embodying my invention consists of three separate heater coils 8, 9 and 10, through which the 60 water to be heated successively flows, a separate gas burner 11 for each coil, a manually controlled supply valve 12, which is actuated by water pressure, and a gas supply valve 13, the operation of which is controlled 65 by the water supply valve.

Each heater coil consists of two layers of horizontally disposed turns, so arranged that the water to be heated enters the outer turn of the lower layer, and is delivered 70 from the outer turn of the upper layer. The turns of the lower layer extend in one direction, communicating with the upper layer at the center of the coil, and the turns of the upper layer extend in the same direction, so 75 that the water circulates through the coil without changing the direction of its spiral motion. The coil 8 communicates with the delivery port 29 of the water supply valve 12 receiving water therefrom, and communicates with the coil 9 and delivers water to the lower layer of turns of that coil. The coil 10 is located between and above the coils 8 and 9 and communicates with the coil 9, and with a delivery pipe 14 of the heater. 85

Each burner 11 consists of a central chamber 15, which communicates with a gas delivery pipe 16, and with which radially extending fingers 17 connect. The fingers 17 are secured to the wall of the chamber 15, 90 and each finger is provided with a line of holes, through which the gas is delivered. Each burner communicates with the delivery port 29 of the gas valve 13 through its communicating pipe 16 and a supply pipe 19, and is located directly under one of the 95 heater coils. The burners are supported by the communicating piping and in turn support the coils. A coil-support piece 21 is formed integrally with each burner 11, and is provided with a vertically projecting extension 22 which projects up through the turns of the adjacent coil. This arrangement supports and holds the coils firmly in place. 100

A pilot burner 24 is provided for the heater and consists of three branches, each of which extends into close proximity with one of the burners 11 and is adapted to light the burner when the gas valve 13 is opened. 110

The pilot burner communicates by means of piping 26 with the casing of the valve 13 on the admission side, so that the supply of gas is not affected by the operation of the valve. A valve 25 is provided in the piping 26 and is adapted to control the delivery of gas in the pilot burner. This valve may be manually operated and is independent of the valve 13.

10 The water supply valve 12 is inclosed in a casing 27 provided with a water inlet port 28 and a water delivery port 29, and a cover portion 30, which is suitably secured thereto. The port 28 communicates with a 15 source of water supply and the port 29 communicates with the coil 8.

The valve 12 is actuated by means of a lever 31 and the water pressure of the source of water supply. The water pressure tends 20 to open the valve and to hold it in the open position while the lever 31, and the intermediate coöperating parts operate in opposition to the water pressure to close the valve and to hold it in the closed position.

25 The valve 12 consists of a disk provided on one side with an upwardly projecting cylindrical flange 32, and is adapted to reciprocate within its casing to control the delivery of water to the coils. A cylindrical 30 extension 33 formed on the cover 30 coöperates with the flange 32 and forms a guide for the valve. A washer 34 is provided on the lower side of the disk which seats, when the valve is closed, an annular seat 35, 35 formed integrally with the casing, and located around the inlet port 28. The operating lever 31 is pivotally mounted on a bracket 36 formed on or secured to the valve casing cover 30 and actuates a cam 37. The 40 operating face of the cam 37 contacts with and reciprocates a plunger 38, which is mounted in a vertically extending recess 39 formed in the cover 30 and extending down and partially through the extension 33. A 45 loose link 40 projects up through an opening formed in the bottom of the extension 33, into the recess 39 and is held in place between the plunger 38 and the valve 12 by the water pressure on the lower face of the 50 valve. With this construction, the valve 12 operates freely and there is no tendency to bind, even though the cylindrical flange 32 and the operating plunger and link are not in absolute parallel alinement. The cam 37 55 is so constructed that when the lever 31 is moved from a horizontal position at the left of the bracket 36 (Fig. 2) to a vertical position, it forces the plunger 38 and consequently the valve disk down and closes the 60 valve. When the lever is moved from the vertical to the horizontal position, it permits the valve 12 to open in response to the water pressure below the disk. A seat 41 is provided on the bottom face of the ex- 65 tension 33, upon which the valve 12 seats

when in the open position. A washer 42 is mounted on the upper face of the disk 12 and engages the seat 41, when the valve is open. With this arrangement of the washers 34 and 42, it is not necessary to provide stuffing-boxes for the valve. When the valve is closed, water is excluded from the casing by the packing 34, and, consequently, there is no tendency for the water to leak past the link and the operating plunger; 70 and when the valve is open, the packing 42 prevents leakage past the link and plunger. 75

The gas valve 13 is operated by the plunger 38 and is so arranged that it opens simultaneously with the water supply valve 12. 80 The valve 13 is substantially the same as the valve 12, except that it is provided with a valve stem 45, which is loosely secured to the valve, in place of the plunger 38 and the link 40 of the valve 12. This stem 45 projects upwardly through the cover portion and is reciprocated by means of an arm 46 mounted on the plunger 38. The valve stem 45 extends through an opening in the end of the arm 46 and is operatively secured to it 90 by means of coil springs 47, which surround the stem and which are located on each side of the arm. The springs are provided so that each valve 12 and 13 will seat, either in their open or closed position, and regardless of the difference in travel between the valves. 95

The heater coils and burners are inclosed within a casing 50, which, if desired, may be provided with a vent flue for the products of combustion. The casing may be provided with supporting legs 51, or it may be adapted to be secured to supporting brackets for the purpose of mounting it on a vertical wall. 100

The operation of the apparatus is as follows: When the lever 31 is moved from the vertical to the horizontal position, the water pressure below the valve 12 exerts sufficient force to raise the valve 12 and the valve 13 from their seats. This causes a flow of water through the successive coils of the heater and also delivers gas to the separate burners of the heater. The burners are lighted by the pilot lights, which are, of course, burning prior to shifting the lever 31. The water passing through the first coil is heated by the burner under the coil and is further heated as it passes through the successive coils 9 and 10. With this arrangement, hotter water can be delivered for the same amount of gas burned, for the reason that every portion of each coil is exposed to the hottest part of the flame of its adjacent burner. When the lever arm 31 is moved from the horizontal to the vertical position, the cam 37 operates to move both the valves 12 and 13 to their closed position. This shuts off the water to the coils and simultaneously the gas to the burners. One ad- 115

vantage of this valve arrangement is that the gas valve will not open if the water supply has been shut off. Under such conditions the shifting of the lever 31 will have 5 no effect on either of the valves, and they will both remain closed. Both the valves will remain closed until water is again delivered to the valve 12, when it will open and also open the valve 13.

10 What I claim is:

1. In combination with a water heater, a valve for controlling the delivery of water thereto, comprising a disk, an inclosing casing for said disk, and means provided on 15 said casing whereby the water pressure operates to move said disk to the open position, a manually actuated lever for moving said disk in opposition to the water pressure to the closed position, a plunger between said 20 lever and said disk and actuated thereby, and a gas valve operated by said plunger.

2. In combination with a water heater, a valve for controlling the delivery of water thereto, comprising a casing, a disk responsive 25 to water pressure within said casing, a lever for positively moving said disk to and locking it on its seat to close said valve, a plunger located between said lever and said disk, and a gas valve operated by said 30 plunger.

3. In combination with a water heater, a valve for controlling the delivery of water thereto, comprising a casing, a pressure responsive disk mounted in said casing, and a manually actuated means for contacting 35 with said disk and for positively moving said valve to the closed position, a gas valve, and means actuated by said manually actuated means for controlling the operation of 40 said gas valve.

4. In combination with a water heater, a valve for controlling the delivery of water thereto, comprising a casing, and a disk mounted in said casing responsive to water 45 pressure for opening said valve, manually actuated means for positively closing said valve, which is incapable of moving said disk to open said valve, and a gas valve actuated by said water valve for delivering 50 gas to said heater.

5. In combination with a water heater, a valve for controlling the delivery of water to the coils thereof, comprising a casing having a water inlet and a water deliv-

ery port, a disk in said casing and movable in response to water pressure to open the valve, a manually actuated plunger for moving the disk to close the valve, said plunger being incapable of opening the valve, a gas valve and a spring-controlled 60 lost motion connection between said plunger and said gas valve whereby the plunger is capable of opening and closing the gas valve substantially as described.

6. In combination with a water heater, a valve for controlling the delivery of water to the heater, comprising a casing having an inlet and a delivery port, a disk in the casing for controlling the delivery of water therethrough and movable in response to 65 water pressure to open the valve, a plunger for closing the valve which is actuated by the disk during its opening movement and is incapable of actuating the disk to open the valve, a lever for moving said plunger to close the valve, and a gas valve controlled by 70 said plunger.

7. In a water heater, a valve for delivering water thereto, comprising a casing having an inlet port and a delivery port, a disk 80 for controlling the delivery of water through the casing and movable in response to water pressure for establishing communication between the ports, a plunger supported by said disk for moving the disk to close the 85 inlet port and incapable of moving it to open the valve, a lever cam for moving the plunger to close the valve and for locking the valve on its seat, a gas valve, and means actuated by the plunger for controlling the 90 operation of the gas valve.

8. In combination with a water heater, a valve for controlling the delivery of water thereto, comprising a casing having inlet and delivery ports, a disk in said casing and 95 movable in response to water pressure to open the valve, a loosely mounted plunger contacting with said disk and extending through said casing, manually actuated means for engaging said plunger to positively close said valve, a gas valve, and means actuated by said manually actuated 100 means for controlling the operation of the gas valve.
